FULL-FASHIONED KNITTING MACHINE

Emil F. Richter, Philadelphia, Pa., assignor to
 Artercraft Silk Hosiery Mills, Inc., Philadelphia,
 Pa., a corporation of Delaware

Application May 22, 1936, Serial No. 81,170

4 Claims. (Cl. 66—127)

This invention relates to full fashioned knitting machines and more particularly to improvements in the mechanism for actuating the thread carrier bars of such machines.

Full-fashioned machines of the type to which this invention appertains are characterized in that they are provided with a plurality of yarn carrier bars which extend longitudinally of the machine, each of these bars being provided with as many thread carriers as there are knitting sections to the machine. These thread carrier bars, which may number as many as eight or more per machine, are respectively reciprocated in such manner as to cause the thread carriers to travel back and forth to lay the thread in front of the sinkers and dividers which are respectively associated with the banks of needles of the several sections of the machine.

It is among the objects of the present invention to provide in a full-fashioned knitting machine a mechanism which is automatically operative to actuate in predetermined sequence two or more of the carrier bars of the machine, the operation being such that when separate yarns of identical physical characteristics are respectively delivered to the thread carriers of the several carrier bars the several yarns so employed may be indiscriminately distributed throughout the fabric being knitted as to produce an exceedingly uniform appearance in the texture of the fabric, all shadows, stripes, rings and the like being substantially eliminated.

A further object of the invention is to provide a mechanism which is automatically operative to actuate the carrier bars in predetermined regular or irregular sequence, this mechanism being accordingly operative to so govern the operation of the selective mechanism that any given carrier may be operated successively any desired number of times before another carrier is operated.

Other objects and advantages of the invention will appear more fully hereinafter.

The invention consists substantially in the combination, construction, location and relative arrangement of parts, all as will appear more fully hereinafter, as shown in the accompanying drawings and as finally pointed out in the appended claims.

In the said drawings:

Figure 1 is an end elevational view of a full fashioned knitting machine embodying the carrier selector mechanism constructed in accordance with the present invention;

Figure 2 is a vertical sectional view of the upper part of the machine;

Figure 3 is an enlarged frontal view of the carrier-bar engaging device and parts associated therewith;

Figure 4 is a front elevational view of the part of the machine embodying the selector mechanism of the present invention;

Figure 5 is a view of the selector actuating mechanism;

Figure 6 is a view of the steadyng mechanism;

Figure 7 is a view of the mechanism for changing the position of the carrier-bar engaging device;

Figure 8 is a partial view of the mechanism for governing the operation of the selector mechanism; and

Figures 9 and 10 are side elevational and top plan views of the governing mechanism associated with the selector actuating mechanism.

Referring now to the drawings wherein the invention has been illustrated as being embodied in a full-fashioned flat type knitting machine, it will be observed that the thread carrier bars to which reference has heretofore been made are designated generally by the reference numeral 10, it being understood that in accordance with standard practice in the art these carrier bars, which extend in substantially parallel relation longitudinally through the entire length of the machine, are disposed at an elevation somewhat above and immediately to the rear of the longitudinally spaced banks of needles (not shown). It will be observed that in the machine illustrated eight thread carrier bars 10 are employed, the number of which may be varied, accordingly as the machine may be a "legger," a "footer" or a "single unit" machine, from two to eight or more bars.

Inasmuch as the operation of the knitting machine considered as a whole, including the operation of the narrowing motion and of the Coulier and friction mechanisms, remains unaltered and unaffected by the present invention, it is not deemed necessary herein to describe any parts of the knitting machine except such as relate peculiarly to and cooperate with the thread carrier bars and those parts of the present invention which are associated therewith, it being understood, of course, that each thread carrier bar 10 is provided with as many longitudinally spaced thread carriers (not shown) as there are sections or knitting heads to the machine, any suitable means being employed for delivering to each thread carrier a thread or yarn from an individual

cone. These several yarns thus severally delivered to the knitting head of the machine may be identical in their physical characteristics, such as color, denier, twist, material, etc., or they may be radically dissimilar in these characteristics, depending upon the type of fabric to be knitted. Thus, if it be desired to knit a hosiery fabric the texture of which is desired to be uniformly the same throughout and wherein all shadows, rings and other defects due to inherent variations in the physical characteristics of a single length of yarn are desired to be eliminated, by delivering a plurality of similar yarns from individual cones to a number of thread carriers so that each carrier cooperates with the needle bank to produce a separate course of knitted loops with no two adjacent courses formed of the same length of yarn, any variations in the physical characteristics of the yarns employed will be so distributed through the fabric as not to appear as stripes or shadow lines therein.

On the other hand, a plurality of yarns of distinctly different physical characteristics may be selectively delivered to the knitting head of the machine to produce an entirely different effect in the knitted fabric, wherein yarns of different physical characteristics are employed in such manner that no adjacent or successive courses of the knitted fabric are formed of the same length of yarn. The present invention facilitates the production of knitted fabrics wherein the interlooped courses thereof are formed of different yarns, regardless whether the latter are similar or dissimilar in their physical characteristics, and moreover permits the several different types of yarns to be distributed throughout the knitted fabric in accordance with a predeterminedly selected regular pattern or non-uniformly or irregularly, as may be desired, the mechanism being so operative that it is unnecessary for a particular bar to operate constantly in fixed sequence with respect to the remaining bars. In other words, it is possible by means of the mechanism to be presently described for the several carrier bars to operate sequentially or one or more of the bars may be thrown into operation more or less frequently than are the remaining bars.

As has already been mentioned, the several thread carrier bars 10 are arranged for individual reciprocation longitudinally of the machine by a mechanism not shown herein but which is well understood in the art, this mechanism being operative to longitudinally shift an arm 11 which is adapted to selectively engage one or the other of the several carrier bars. This bar-engaging arm 11 is slidably mounted within a supporting member 12 therefor having a trunnion 13 which is splined upon a horizontally disposed rock shaft 14, the member 12 being longitudinally slidable upon the shaft 14 in such manner that when the arm 11 is in engagement with one or the other of the yarn carrier bars 10 the reciprocable movement of the member 12 will be imparted to that one of the carrier bars with which the arm 11 is in engagement. Normally, the arm 11 is in the depressed position relatively to its supporting member 12, as shown in Figures 2, 3 and 4, said arm being provided with a forwardly projecting lifting handle 15 for raising the arm into inoperative position with respect to the carrier bars.

Formed as a part of the trunnion 13 is an upper body member 16 through which longitudinally extends a bar 17, this latter bar being disposed just above and in parallel relation to the rock shaft 14. Fixed to the rock shaft 14 at

a point spaced from the supporting member 12 (see Figure 4) is an arm 18 provided in its free upper extremity with a pin 19 extending in a direction parallel to the rock shaft. A detent 20, suitably pivoted upon a fixed part of the machine, is arranged to ride upon this pin 19 and is provided with a depression 21 within which the pin is adapted to seat, as shown in Figure 1, to lock the machine for regular operation, i. e., for normal operation independently of and uninfluenced by the mechanism of the present invention. It will be observed that when the pin 19 engages the pivoted detent 20, the arm 18 is locked against movement in consequence of which the rock shaft 14 is restrained against oscillatory movement with the carrier-bar engaging arm 11 in the inoperative (full-line) position shown in Figure 2.

Connected to the bar 17 and extending rearwardly and downwardly thereof is a rod 22, a pull 20 upon which in the direction of its length will result in rotating the rock shaft 14 sufficiently to present the carrier-bar engaging arm 11 in position to engage one or another of the carrier bars 10. It will be understood, of course, that in order to effect this result the locking arm or detent 20 must first be lifted out of engagement with the pin 19 thereby permitting the necessary oscillatory movement of the rock shaft 14, the supporting member 12 and the pin-equipped arm 18 as a unit. The mechanism for effecting this oscillatory movement will now be described, it first being observed that in the machine illustrated in the drawings this mechanism is designed for automatic selective actuation of only three of the eight carrier bars shown, namely, the carrier bars designated 10a, 10b, and 10c. Obviously, by simple modification of the mechanism shown, carrier bars other than those just designated, or in addition thereto, may be actuated.

Extending longitudinally of the machine in parallel relation to and spaced somewhat upwardly and to the rear of the rock shaft 14 is a shaft 23, this shaft being journaled for rotation in clockwise direction when viewed from the right-hand end of the machine, as shown in Figure 4. Keyed to the shaft 23 in longitudinally spaced relation are a ratchet 24, a hold down or setting wheel 25, and a carrier bar selector or cam wheel 26. Operatively associated with the ratchet 24 is a pawl 27 which is pivotally mounted, as at 28, to the free extremity of a shoe 29 rotatably journaled upon the shaft 23 in abutting relation to the ratchet 24. The pawl 27 is provided with a laterally extending pin 30 for a purpose which will be apparent hereinafter. Pivotally connected to the ratchet shoe 29, as at 31, is a downwardly extending rod 32 the lower end of which is connected to a bell crank lever 33 which is suitably journaled upon the frame of the machine, as at 34. The forward extremity of this bell crank lever 33 is provided with a cam roller 35 which is adapted to engage the perimetral edge of a cam 36 keyed to the main shaft 37 of the machine. This cam 36 is elongated to provide a high section 38 and a low section 39 and it will be understood that for each complete rotation of the cam 36, each of the carrier bars to be operated by the present mechanism makes a complete stroke in either direction. It will also be apparent that as the high section 38 of the cam engages the cam roller 35, the bell crank lever 33 acts to push the rod 32 upwardly in consequence of which the pawl 27, when in engagement with the ratchet 24 as shown in Figure 5, rotates

the ratchet in the direction of the arrow to the extent of one tooth thereof. Thus, the teeth of the ratchet wheel 24 are successively engaged by the pawl 27 and the ratchet wheel 24 is thereby 5 rotated step by step for each revolution of the cam 36 and for each stroke in a given direction of one of the carrier bars 10a, 10b and 10c.

The hold down or setting wheel 25 is of circular outline and is provided in the rim thereof 10 with a plurality of notches which correspond in number to the number of teeth on the ratchet wheel 24. Operatively associated with this hold down wheel is a spring pressed detent 40, the free extremity of which is provided with a projection 41 which is adapted for successive seating in the several notches 42 of the hold-down wheel. The setting of the latter is such with respect to the setting of the ratchet wheel that as the ratchet wheel is rotated to the full extent 20 of a single tooth, the projection 41 on the detent 40 seats within a notch 42 of the hold-down wheel to prevent back lash or any loose play of the ratchet wheel.

The carrier bar selector or cam wheel 26 is 25 most clearly shown in Figure 7 wherein it will be observed that it is in the form of a circular disc 43 keyed to the shaft 23 and having fixed thereto a plurality of cam elements 44, each of which is provided with a high surface 45 and a low surface 46. The portions of the rim of the disc 43 which lie between the elements 44, which portions are designated by the reference numeral 47, constitute the low spots of the cam wheel. The latter is thus provided with a plurality of 30 cam surfaces 45, 46 and 47 arranged in similar series spaced uniformly about the circumference of the carrier bar selector 26. As clearly appears in Figure 7, the selector disc 43 is provided with six cam elements 44 detachably secured to the disc, thereby providing a total of 35 eighteen cam surfaces, surfaces 45, 46 and 47 repeated six times, which correspond in number to the number of teeth on the ratchet 24 and the number of notches on the hold-down wheel 25. 40 Inasmuch as the ratchet wheel 24, the hold-down wheel 25 and the carrier bar selector disc 26 are all keyed to the same shaft 23, it will be apparent that as the ratchet wheel is successively ratcheted by its pawl 27 for each revolution of the 45 main cam 36, the carrier bar selector 26 will be correspondingly rotated step by step to successively present the cam surfaces 45, 46 and 47 thereof at a given point. Operatively associated with the carrier bar selector disc is a bell 50 crank lever 48 which is suitably journalled upon a fixed shaft 49, the upper arm 50 of this bell crank lever being equipped with a cam roller 51 for successive engagement by the several cam surfaces of the carrier bar selector disc. The 55 opposite arm 52 of the bell crank lever 50 is loosely connected, as by a pin and slot connection 53 (see Figure 1), to the lower extremity of the rod 22 heretofore described. A tension spring 54 extends between the lower end of the bell 60 crank lever and a fixed point 55 on the machine, this spring serving to normally urge the cam roller 51 in contact with the cam surfaces of the carrier bar cylinder disc 26.

The mechanism as just described above is all 65 that is required if it is desired merely to operate the carrier bars 10a, 10b and 10c selectively in predetermined regular sequence. This operation is effected as follows. The main cam 36 which is fixed to the main shaft 37 of the machine operates to depress the cam roller 35 for each stroke 70

of one of said carrier bars and in turn causes the ratcheting mechanism to ratchet step by step in clockwise direction the shaft 23 upon which is keyed the carrier bar selector mechanism shown in Figure 7. Successive movements of the shaft 5 23 present in sequence the successive cam surfaces of the carrier bar selector mechanism against the cam roller 51 in consequence of which the bell crank lever 48 operatively associated with this selector mechanism is rotated about its shaft through successively different angles to present the arm 11 for engagement with one or another of the carrier bars 10a, 10b or 10c. Thus, when the selector wheel is in the position shown in Figure 7 with one of the highest cam surfaces 15 45 thereof in engagement with the cam roller 51, the bell crank lever 48 will be shifted in clockwise direction to its maximum extent to thereby shift to its maximum extent the rod 22 and so cause the carrier bar-engaging arm 11 to shift about the 20 axis of the rock shaft 14 to an extent sufficient to permit the arm 11 to engage the carrier bar 10c. Upon the succeeding rotation of the main cam 36, the pawl 27 of the ratcheting mechanism advances the ratchet wheel 24 to the extent of 25 the next tooth in consequence of which the intermediate cam surface 46 is presented against the cam roller 51, whereupon the rod 22 is retracted sufficiently to present the carrier bar-engaging arm 11 in engagement with the carrier 30 bar 10b. Upon further ratcheting of the ratchet 24, the lowest cam surface 47 of the carrier bar selector mechanism is engaged by the cam roller 51 with the result that the rod 22 is still further retracted to cause the arm 11 to engage the carrier bar 10a. This cycle of operation is repeated 35 so that for each ratcheting step of the ratchet wheel 24, which occurs for each complete revolution of the main cam 36, a separate cam surface (45, 46 or 47) is presented against the cam roller 51 to correspondingly rotate the bell crank lever 48 about its pivot 49 and so cause movement of the rod 22 sufficiently to effect engagement of the carrier bars 10a, 10b and 10c successively by 40 the arm 11.

It may be desired on occasion to operate any one of the carrier bars 10a, 10b or 10c a number of times in succession, thereby obtaining an irregular sequence of operation of these bars, as when it is desired to produce novelty effects in the knitted fabric. This irregular operation may be effected manually by the simple expedient of lifting the pawl 27 out of engagement with the ratchet 24, in which case, of course, there is no further rotation of the shaft 23 and the carrier-selector disc 26 remains stationary as does the bell crank lever 48 to thereby retain the arm 11 in engagement with the particular carrier bar with which it is already engaged. Thus, by easy manual manipulation of the pawl 27 any 50 one of the carrier bars 10a, 10b or 10c may be continued in successive operation to knit as many 55 courses as may be desired.

This same result may also be effected automatically by the auxiliary mechanism now to be 60 described, it being important to observe in this connection that this auxiliary mechanism is operative to throw into operation in accordance with a predetermined sequence selected carrier bars, any one of which may be operated to knit two 65 or more courses of the fabric before another bar is operated. This auxiliary mechanism essentially consists of an endless pattern chain 56 which travels over sprockets 57 and 58 suitably disposed in vertically spaced relation. Prefer- 70

ably, the upper pair of sprockets 57 is journalled for rotation about a fixed shaft 59 disposed to the rear of the shaft 23, while the lower pair of sprockets 58 is maintained in suspended relation to the upper sprockets by means of a tension spring 60 or its equivalent, such as a weight.

Fixed to the upper sprocket 57 for rotation therewith is a ratchet 61 with which is operatively associated a pawl 62 pivotally carried upon the outer extremity of a shoe 63 in a manner similar to the pawl mounting of the ratcheting mechanism shown in Figure 5. A rod 64, pivotally connected, as at 65, to the shoe 63, extends downwardly with its lower end connected to a bell crank lever 66 pivoted upon the shaft 34 of the bell crank lever 33. A cam roller 67 fitted upon the free extremity of the lever 66 engages a second main cam 67a keyed to the main shaft of the machine, the cam 67 being somewhat similar in shape to the cam 36 and operating in unison therewith.

The pattern chain 56 as such is of the conventional construction ordinarily employed in full-fashioned knitting machines insofar as it consists of a plurality of longitudinally spaced cross bars 68 successive pairs of which are employed to support in predeterminedly spaced relation a plurality of pattern chain buttons 69. It will be understood, of course, that the arrangement of the pattern chain relatively to the other parts of the machine is not the conventional arrangement but instead is one peculiar to the machine of the present invention. It will be observed further that the pattern chain buttons 69 are preferably arranged in two rows laterally spaced apart, although the buttons in each of these rows are not necessarily uniformly spaced apart longitudinally of the chain. These buttons 69 operate in the manner and by the means presently to be described to throw the pawl 27 out of engagement with the main ratchet wheel 24. Inasmuch as the ratchet wheel 61 which is immediately associated with the pattern chain is provided with a number of teeth corresponding to the number on the main ratchet wheel, it will be apparent that for successive revolutions of the secondary cam 67a, the pattern chain will be stepped along its orbit of movement so as to present opposite a given point successive pairs of button-supporting cross bars 68. This means, of course, that for each stroke of a carrier bar a pair of button supporting bars of the pattern chain is presented at the said given point. Of course, not all of the successive pairs of button supporting bars of the pattern chain are fitted with the buttons 69 which results in depressions 70 being formed between successive buttons.

Operatively associated with the pattern chain is a bell crank lever 71 which is journalled, as at 72, upon an arm 73 suitably fixed to the machine. The arm 74 of the bell crank lever 71 is disposed in such manner that it overlies the top of the pattern chain for engagement by the buttons 69 as the latter are successively presented in the given position above mentioned which is just beneath the outer extremity of the bell crank lever arm 74. Preferably, this outer extremity of this arm 74 is of a width sufficient to encompass both of the laterally spaced rows of buttons 69.

The opposite arm 75 of the bell crank lever 71 extends downwardly of its pivot point 72 and is loosely connected, as at 76, to one end of a pawl-releasing cam member 77 which is mounted for oscillation about the shaft 23 in a vertical plane intersecting the pin 30 of the main ratchet pawl

27. This pawl-releasing cam member 77 is provided with a forwardly projecting rounded nose 78 which is adapted upon rotation thereof in clockwise direction to engage the said pin 30 of the pawl 27 to effect the disengagement of the latter from the ratchet 24. This rotation of the cam 77 to effect the release of the pawl 27 is obtained by means of the bell crank lever 71 contacting with the buttons 69 on the pattern chain and the buttonless spaces therebetween. It will be apparent that as the button 69 rides beneath the arm 74 of the bell crank lever 71, it causes the latter to shift in such position as to rotate the pawl-releasing cam 77 sufficiently to effect disengagement of the pawl 27 from the main ratchet wheel 24. Obviously, if the buttons 69 of the pattern chain were so arranged that they successively and without interruption engaged the arm 74 of the bell crank lever 71, the pawl 27 would be maintained constantly out of engagement with the main ratchet with the result that the machine would continue to reciprocate a single carrier bar. By suitably spacing the buttons, the operation of the various carrier bars is easily regulated, it being understood in this connection that the selector mechanism for selecting and controlling the operation of the several bars in predetermined regular or irregular sequence is dependent entirely upon the raising and lowering of the arm 74 of the bell crank lever 71 by the buttons 69 and buttonless spaces therebetween on the pattern chain.

It will be understood, of course, that the invention is susceptible of various changes from time to time without departing from the real spirit or general principles thereof and it is accordingly intended to claim the same broadly, as well as specifically, as indicated by the appended claims.

What is claimed as new and useful is:

1. In a full-fashioned knitting machine, in combination, a plurality of reciprocable thread carrier bars, means for effecting the individual reciprocation of said bars in a predetermined order, said means including a bar-engaging arm slidably mounted upon a rock shaft, and means for angularly adjusting the said rock shaft whereby to present said arm for engagement with the several carrier bars in the desired predetermined order, said means including a cam wheel, a lever operated by said cam wheel, the cam wheel being intermittently actuated through a ratchet mechanism for actuating said lever through strokes of varying degree.

2. In a full-fashioned knitting machine, in combination, a plurality of reciprocable thread carrier bars, means for effecting the individual reciprocation of said bars in a predetermined order, said means including a single bar-engaging arm slidably mounted upon a rock shaft, a lever system operatively associated with the rock shaft for effecting the angular adjustment of the latter about the axis of said shaft, and means including a ratchet-operated cam wheel having a series of circumferentially spaced identical groups of gradient cam surfaces for automatically actuating said lever system through varying angular degrees at the instant any one of said carrier bars reaches the limit of its stroke in either direction.

3. In a full-fashioned knitting machine, in combination, a plurality of parallel thread carrier bars, a reciprocating arm adapted to engage any one of said bars for effecting the movement thereof in either direction, a lever operative upon said

5 arm to effect its engagement with one or the other of said bars selectively as desired, ratchet-operated means for causing said arm to rock outwardly and across the several carrier bars, and means automatically operative to render inoperative said ratchet-operated means to permit the successive operation of a given carrier bar, said last-mentioned means including a cam-operated lever system operating a pattern chain, said 10 pattern chain acting conjointly with a cam and lever assembly to intermittently disengage the pawl of the aforementioned ratchet.

4. In a full-fashioned knitting machine, in combination, a plurality of parallel thread car-

rier bars, a rock shaft, a bar-engaging member non-rotatably but slidably mounted upon said rock shaft, a cam-operated lever system operative to rock said shaft through various fixed angles whereby to present said member in position for selective engagement with the several carrier bars, ratchet-controlled means for fixing the various positions which said lever system may assume, and means operative to actuate the ratchet to the extent of one step as a particular carrier 10 bar in motion reaches the limit of its stroke in either direction, said last-mentioned means consisting of a cam-operated lever system.

EMIL F. RICHTER.
